UNITED STATES PATENT OFFICE.

JOHN B. VAN HOUTEN, OF NEWARK, NEW JERSEY.

DESIGN FOR AN EAR-RING PENDANT.

SPECIFICATION forming part of Design No. 14,863, dated March 4, 1884.

Application filed November 30, 1883. Term of patent 7 years.

To all whom it may concern:

Be it known that I, JOHN B. VAN HOUTEN, a citizen of the United States, residing at Newark, in the county of Essex and State of New Jersey, have invented and produced a new and original Design for Ear-Ring Pendants; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification, in which—

15 Figure 1 is a front, and Fig. 2 an edge or a side view of my newly-designed ear-ring, which two views fully illustrate my design.

The distinguishing feature of this design is in the peculiar form and configuration of the 20 pendant, which is as follows: The body thereof

is circular in form, showing a split ring, the outer surface or edge of which is corrugated or scalloped, as indicated by *a*, the ends being connected by a bow, *b*, with which the ear-wire *c* engages, and below which, at or near the 25 center of the ring, depends a gem-setting, *d*, all as shown in the drawings.

The surface-engraving may be varied to suit the taste, and forms no part of my design.

I claim—

30 The design for an ear-ring pendant herein shown and described.

In testimony that I claim the foregoing I have hereunto set my hand this 28th day of November, 1883.

JOHN B. VAN HOUTEN.

Witnesses:

OLIVER DRAKE,
CHARLES H. PELL.
